UNITED STATES PATENT OFFICE.

GEORGE M. WOODRING, OF NEW CASTLE, PENNSYLVANIA.

COMBINED TROUSERS-PROTECTOR AND APRON.

1,177,159.

Specification of Letters Patent. Patented Mar. 28, 1916.

Application filed November 12, 1914. Serial No. 871,748.

To all whom it may concern:

Be it known that I, GEORGE M. WOODRING, a citizen of the United States, residing at New Castle, in the county of Lawrence and 5 State of Pennsylvania, have invented certain new and useful Improvements in Combined Trousers - Protectors and Aprons, of which the following is a specification.

This invention relates to improvements in 10 combined aprons and trousers protectors.

The invention has for its object to provide for protecting or reinforcing the trousers, more particularly at the seat, especially for 15 school-boys, draymen, chauffeurs, drivers, office-clerks and those whose occupation compels their sitting upon stools and like seats; also to provide protection for the clothing at the front in addition to affording the aforesaid protection.

20 A further object is to provide for carrying out the above named ends in a simple, inexpensive and effective manner, and with facility.

The invention consists therefore of facilities applicable for use in front of the clothing and to the seat, substantially as herein-after more fully disclosed and defined by the appended claim.

25 In the accompanying drawing is illustrated the preferred embodiment of my invention, wherein it will be understood that various changes and modifications may be made as to the detailed construction and arrangement of parts without departing from 30 the scope of the claim, and in which drawings:—

Figure 1 is a perspective view of a figure of a man, with my invention shown applied thereto. Fig. 2 is a detached plan view of 40 the device spread out or in extended position. Fig. 3 is a detached perspective view of the device as when buttoned and as in the position it partially assumes when worn.

45 In making the seat protecting member 1, I suitably cut or form the same from suitable material, which may be leather, corduroy, cloth or rubber, the use of which is preferably for wear and accordingly for protection or reinforcing purposes. The blank or 50 resultant 1, as produced from so cutting the named material assumes the form as disclosed by Fig. 2, the same being of generally rectangular outline with its bottom edge produced upon an approximately V-shaped 55 contour, as at 2, the apex or taper thereof being in the longitudinal center of the blank,

as at 3, which said blank is bodily folded in said longitudinal center from a point quite close to the taper or apex 3, upwardly clear to, and carrying slightly downwardly and 60 centrally the upper edge or end of the blank, as at 4. Said upper edge or end of said blank terminates at one edge in lateral strap-like extension 5, having a button-hole or eye 6 therein, the purpose of which, as disclosed 65 by Fig. 1, is to effect the holding the device at that point upon the wearer. The blank 1 has its lower portion provided at its lateral edges, with lateral tabs 8, these all being equipped with hooks, glove-fasteners or 70 buttons 9 at their outer ends, the purpose of which will be apparent later. An additional or auxiliary piece or member 11 with a tapered crotch-reinforcing portion 12 attached or sewed to the upper end thereof and to the 75 blank 1 at the point 3 as clearly seen in Figs. 2 and 3, is provided with a plurality of strap-like extensions 13, all of which are provided with button-holes or eyes 14 which are adapted for engagement with the buttons, hooks or other fastenings of the tabs 80 of the body 1, as said tabs are brought from between the legs around to the front of the legs of the wearer, as clearly shown in Figs. 1 and 3. The protector is thus adapted to be 85 applied or fitted over the trousers to reinforce or protect, particularly the seat, and accordingly guard against undue or premature wear that point as is apparent, while 90 said protector may be equipped with a pneumatic or resilient cushion in the seat-portion, or it may be devoid of such a cushion, as may be desired.

As shown in Figs. 1 and 2 I suitably cut or form from like material as above indicated, the apron 15, with its upper narrow-end portion 16, which has attached thereto a loop-forming member or strap 17 for passing around the neck, adapted to extend in front of the vest or shirt front from the 100 lower portion 8 of the apron extending downwardly and adapted to protect the upper or main front portions of the legs, this portion being of generally rectangular outline, as indicated in Fig. 2. This portion 18 105 has attached thereto, upon its underside loops 19 through which is passed the strap like extension 5 of the seat-protecting member 1, a button hole 20 being provided in the upper left-hand corner of the rectangular portion 18 of the apron 15 for the reception or engagement therewith of the button near 110

the upper right-hand corner edge of the portion 18. Adjacent to the button 7 of the member 1 is an additional button 7^a, on the latter member, arranged to be received or engaged by a button-hole 6 in the strap like extension 5 of the member 1, this arrangement, it will be seen, providing for the attachment of the apron to the seat-protecting member. It is apparent that by suitably 10 manipulating the above referred to buttons with respect to the requisite button hole or holes the apron may be partially detached or wholly detached.

It is thought that it has been made fully 15 apparent that the use of the device or protector in the various relations or capacities recited in the syllabus or introductory clause to the specification proper has been clearly disclosed by the foregoing description taken

in connection with the accompanying drawing.

I claim:—

A device of the type described, including an apron, in combination with a seat-protecting member, said seat-protecting member being provided at one edge of its upper end with a strap-like extension having a button-hole at its free end, said seat-protecting member having buttons at the same end upon its opposite portion and said apron 30 having upon its underside loops receiving said strap-like extension.

In testimony whereof I affix my signature in presence of two witnesses.

GEORGE M. WOODRING.
